UNITED STATES PATENT OFFICE

MARIUS J. WISBY, OF RACINE, WISCONSIN.

PHONOGRAPH HORN.

Application filed July 3, 1922. Serial No. 572,719.

To all whom it may concern:

Be it known that I, MARIUS J. WISBY, a citizen of the United States, and resident of Racine, in the county of Racine and State of Wisconsin, have invented certain new and useful Improvements in Phonograph Horns; and I do hereby declare that the following is a full, clear, and exact description thereof.

My invention refers to phonographs, and 10 it has for its object to provide an amplifying tone horn for such instruments having an attachment whereby the tone is modified or softened to absorb the metallic sound or vibrations of the instrument.

15 The specific object of my invention is to provide, in connection with the standard type of tone horn, a compartment having a scroll vent therein and a post associated therewith similar to the scrolls and post of 20 a violin, this compartment being gradually increased in size from the intake neck of the horn to the mouth thereof, and being otherwise closed.

With the above objects in view, my invention 25 consists in certain peculiarities of construction and combination of parts as are hereinafter set forth with reference to the accompanying drawing and subsequently claimed.

30 In the drawings:

Figure 1 represents a sectional elevation of a horn having an attachment at its bottom portion in accordance with my invention, and

35 Figure 2 is a plan view of the same with parts broken away and parts in section as indicated by the line 2-2 of Figure 1.

Referring by characters to the drawing, A represents the top wall of a phonograph 40 cabinet, and B the front wall thereof having an opening C therein. The top wall is also provided with an opening D, to which is connected the restricted neck 1 of a phonograph horn, which horn is curved forwardly 45 and gradually increased in dimensions to form a bell-shaped mouth 2, that is merged into the front wall about the opening C thereof. The main bottom wall 3 of the horn has spaced therefrom an auxiliary wall 4, which wall is merged into the bottom wall 50 near the neck portion 1 of the horn. From this point the auxiliary wall with relation to

the main bottom wall 3, is gradually flared therefrom to form a compartment or chamber 5, increasing in dimensions from the 55 neck of the standard horn to its mouth. The walls 3 and 4 at the mouth of the horn are connected by a lip 6, whereby the auxiliary compartment or chamber is closed.

The auxiliary wall is formed with a vent 60 in the form of a double scroll 7, similar to that usually employed in connection with violin bodies, and between the scroll slots there is placed a vertical sounding post 8, which post connects the auxiliary wall and 65 the main bottom wall 3, and serves, in connection with the scroll vents in the compartment, to soften the tone emitted from the horn, similar to the principles involved in a violin body. 70

It is understood that while no mention has been made of the material from which the horn is manufactured as a whole, obviously the same is composed of wood or other fibre, as such material has been found in practice 75 to produce the most satisfactory results.

While I have shown and described one simple exemplification of my invention, in all of its details, it is understood that I may vary the proportion and structural features 80 within the scope of the appending claim.

I claim:

A phonograph horn comprising a horn portion having a restricted throat and divergent walls extending therefrom, the upper and lower walls being curved and gradually divergent, and the side walls being gradually divergent and straight, one of said curved walls having a pair of spaced apertures, an auxiliary wall merging into such 85 apertured wall adjacent the throat and gradually curving and separating therefrom as the outer end of the horn is approached, a member closing the space between the apertured wall and the auxiliary wall and located 90 adjacent the outer end of the horn, and a support between said auxiliary and apertured walls and contacting with said apertured wall at a point between said apertures. 95

In testimony that I claim the foregoing I 100 have hereunto set my hand at Racine, in the county of Racine and State of Wisconsin.

MARIUS J. WISBY.
